UNITED STATES PATENT OFFICE.

WILLIAM E. STITZER, OF MUSKOGEE, OKLAHOMA.

ATTACHMENT FOR INTERNAL-COMBUSTION ENGINES.

1,351,706.

Specification of Letters Patent. Patented Aug. 31, 1920.

Application filed November 24, 1919. Serial No. 340,173.

To all whom it may concern:

Be it known that I, WILLIAM E. STITZER, a citizen of the United States, and a resident of Muskogee, in the county of Muskogee, 5 and State of Oklahoma, have invented certain new and useful Improvements in Attachments for Internal-Combustion Engines, of which the following is a specification.

My invention is an improvement in attachments for internal combustion engines, and 10 has for its object to provide mechanism for use in connection with lubricator and controlled by the level of the oil in the lubricator, for stopping the motor when the oil falls below a predetermined level, by short 15 circuiting the ignition system.

In the drawings:

Figure 1 is a front view of the lubricator provided with the improved attachment, the 20 attachment being embodied in the lubricator,

Figs. 2 and 3 are sections on the lines 2-2 and 3-3 respectively, of Fig. 1,

Fig. 4 is a side view of the float, 25 Fig. 5 is a vertical section of the lower end of the lubricator,

Fig. 6 is a front view of the attachment wherein the controlling mechanism is independent of the lubricator,

30 Fig. 7 is a section on the line 7-7 of Fig. 6.

In the embodiment of the invention shown in Figs. 1 to 5, the lubricator 1 which is of usual construction, being composed of glass 35 and brass has within the same a float 2, which rises and falls with the level of the lubricant, the float being guided on the tubular structure 3 at the center of the casing, and by a rod 4 which is arranged eccentric to the casing. A rod 5 of suitable conducting material is arranged within the lubricator casing, the said rod extending downwardly from a binding post 6 connected with the top of the lubricator, and 40 insulated therefrom as shown. Referring to Figs. 2 and 3, it will be seen that the float 2 is a split ring, the split being at the contact bar 5. Across this split there is held on the float an arch shaped bar 7 of conducting material, the said bar being held to the float in any suitable or desired manner, as for instance by the bindings 8. This bar 7 is adapted to contact with an angular lug

9 on the lower end of the rod 5, when the float is in lowermost position, that is when 55 the lubricant is about exhausted. The ends of this bar 7 are connected to a strip 10 of conducting material, as for instance copper, which is held on the under face of the float in any suitable or desired manner, and this 60 strip is adapted to engage the bottom of the lubricator casing, when the oil level falls far enough, to complete the short circuit, through the lubricator casing to ground.

In the embodiment of the invention shown 65 in Figs. 6 and 7, an auxiliary casing 11 is provided, which is connected to the lubricator 12 at both ends, as indicated at 13 and 14 respectively, in such manner that the lubricant will stand in the casing 1 at the 70 same level as in the lubricator casing 12. A float 15 is arranged within the casing, and this float carries a contact plate 16 which is adapted to contact with a contact screw 17, connected by a binding post 18 with the casing 11, in insulated relation. The lower face of the float 15 carries a strip 19 of conducting material, which is adapted to contact with the bottom of the casing 11, to short circuit the motor, it being understood 75 that the short circuiting is through the casing 11 to ground.

In operation with either construction, when the lubricant level falls to a point such that the metal strip on the bottom of 85 the float contacts with the lubricator casing, the contact bar 7, or the plate 16 as the case may be will complete the circuit to ground, through the rod 5 or the binding post 18 as the case may be. The ignition being short 90 circuited the motor will stop.

I claim:

In an internal combustion engine, the combination with the lubricator casing, of a normally open short circuiting circuit for 95 the ignition circuit, and means controlled by the level of the oil in the lubricator casing for closing said circuit when said level falls below a predetermined point, said means comprising an arc shaped float, a rod on 100 which the float has guided movement, a contact member connecting the ends of the float, and a rod supported by the casing in insulating relation and having a lug at its lower end for engagement by the contact member. 105

WILLIAM E. STITZER.
